UNITED STATES PATENT OFFICE

GEORGE W. DAVEY, OF LONG ISLAND CITY, NEW YORK

FURNACE WALL

Application filed December 19, 1925. Serial No. 76,549.

My invention relates to furnace wall structures in which an inner wall, built up of a series of superimposed, broken jointed expansion blocks of high refractory materials 5 is positioned and held against a permanent masonry outer wall by a multiplicity of special bonding brick that are interlockable, slidably movable, and integral with the inner wall and horizontally interlockably and movably held in the vertical relation in the outer wall.

One of the objects of my invention is to construct a wall of interlockable high refractory, unit, individually expansible, blocks, 15 inside of an outer wall, holding the inner wall in vertical alignment with the outer wall while the inner wall may freely expand horizontally and vertically.

Another object of my invention is to construct a composite furnace or generator wall consisting of an outer wall of masonry and an inner wall or lining of high refractory materials that will automatically adjust itself to the unequal expansion of the two walls and parts thereof, due to their differences of temperature and simultaneously circulate air between the two walls in proximity to the inner surface of the inner wall to maintain that difference of temperature and with the further object in view of utilizing the heat units for other purposes.

A still further object of my invention is to construct a fixed outer wall of masonry, a horizontally slidable, vertically movable interlockable inner wall of high refractory materials and maintain a uniform air space exposing the maximum area of the inner surface of the said inner wall to a circulatable body of air therein.

40 I accomplish this by utilizing the interlockable unit expansion block referred to in my co-pending application for "improvements in air cooled furnace expansion blocks".

45 The salient features of my invention hereinafter described, pointed out and claimed are illustrated in the accompanying drawings, wherein similar numerals refer to like parts throughout the several views, in 50 which:—

Figure 1 is a plan view of a special brick or block forming part of the interlocking means integral with the inner wall.

Figure 2 is a section of Figure 1 on line 2—2.

55 Figure 3 is a plan view of one of the interlocking blocks integral with the outer wall cooperating with the block shown in Figure 1.

Figure 4 is a section of Figure 3 on line 4—4.

60 Figure 5 is an isometric view of another form of the interlocking means integral with the inner wall.

Figure 6 is an isometric view of a form of 65 interlocking means cooperating with that shown in Figure 5.

Figure 7 is an isometric view of a segmental, interlockable block integral with the inner wall.

70 Figure 8 is an isometric view of a segmental, interlockable block cooperating with the blocks shown in Figure 7 and integral with the outer wall.

75 Figure 9 is an isometric view of another form of interlockable means integral with the outer wall, projecting into the air space between the said walls.

80 Figure 10 is an isometric view of still another form of interlockable means integral with the outer wall, projecting into the air space between said walls.

Figure 11 is a partial section of a furnace wall illustrating how the interlocking means is utilized in a wall.

85 Figure 12 is a partial plan in section of Figure 11.

Figure 13 is a partial section of a generator wall illustrating one form of interlocking means utilized in a generator wall.

90 Figure 14 is a partial plan in section of Figure 13.

95 Figure 15 is a typical elevation of a furnace wall, the arrows illustrating the flow of air therein and the relative position of the blocks.

Figure 16 is an isometric view of one of the spacer or filler brick, slidably interlockable with the bricks illustrated in Figures 1, 2 and 5.

Figure 17 is an isometric view of one of the segmental spacer or filler brick, slidably interlockable with the bricks illustrated in Figure 7.

5 The block 1, shown in Figures 1 and 2, illustrating one form of the interlocking means integral with the inner wall and interlocking by means of the groove 2, tongue 3, notch 18, and boss 19, is substantially rectangular in shape having two bulged portions 4 circular in shape, one on each side of the block, which bulged portion interlocks with the cooperating block shown in Figures 3 and 4.

10 15 The block 5 in Figures 3 and 4 which is one of a pair is integral with the outer wall and when built up therein, the end containing the bulged portion and the bulged portion interlocks therein as illustrated in Figure 11.

20 25 This block 5 has a shoulder 6 fitting against the end 7 of block 1, and a cup shaped opening 8 into which fits the bulged portion 4 of block 1.

The blocks 5 are set in spaced relation in 25 the outer wall 9 so that the block 1 can freely move vertically in the space 10.

30 35 The block 13 shown in Figure 5 is of similar construction as is shown in Figures 1 and 2 except that the V-shaped portion 11 is substituted for the bulged portion 4.

The complementary blocks 12 one of which is shown in Figure 6 has a V-shaped groove or part 14, cooperating with the V 11 in block 13 and as hereinbefore stated the block 13 may 35 move vertically in the space 10.

40 45 Blocks 1 and 13 upon the completion of a wall built up with a series of superimposed, broken jointed, air cooled expansion blocks 16, have their faces 15 flush with the inside face of the blocks 16 and in perfect alignment therewith, as clearly illustrated in Figures 11 and 12.

50 55 It will be noted that in Figure 15 the filler blocks 17 shown in Figure 16 interlock in between the blocks 1, (see Figure 12) in slideable engagement therewith at 20 and that the spaces 22 between the blocks 17 and bricks 1 will allow freely for any horizontal expansion of the wall, while the space 10 compensates for the vertical expansion of the inner wall as a whole.

55 60 The bosses 23 on the outer face of the blocks 16, form a uniform air space 24 between the inner face 21, of the spacer block 17, which is in perfect alignment with the outer face of block 16, and the inner face 9 of the outer wall 25.

65 70 The segmental block shown in Figure 7 is of similar construction as is the block 13 except the inner surface or face 26 and the outer face 27 is curved to conform with the size of the generator in which it is utilized as clearly shown in Figure 14.

75 80 The complementary block 29, to that shown in Figure 7, one of which is shown in

Figure 8, segmental in shape, whose face 30 is flush with the inside of the generator and in alignment with the inner face of the generator and generator spacing blocks, interlocks with block 28 illustrated in Figure 7 70 and provides an expansion space 10 of a character similar to that shown in Figures 4, 6 and 11.

80 85 There is another method of holding or interlocking both the rectangular and segmental blocks in a wall which consists in a pair of blocks, one of which is shown in Figures 9 and 10, that project beyond the inner face 9 of the outer wall 25 into the air passage or space 24, and hold the bonding blocks either 1 or 13 in furnaces or 28 in generators as clearly shown in Figures 13 and 14.

85 90 The blocks 31 project beyond the inner face 9 of the outer wall 25, arranged in pairs in spaced relation to each other, interlockable with a block or brick similar to 13 or 1 and are provided with curved surfaces 32 as clearly shown in Figures 9, 10 and 13.

90 95 Having thus described and illustrated the preferred embodiment of my invention I do not desire to limit myself to the exact construction shown except so far as the same may be specifically claimed, since it is evident that modifications may be made without departing from the spirit of the invention or scope 95 of the claim.

I claim:—

100 A tie block for a double wall construction, shouldered on two opposite faces for interlocking sliding engagement with one wall structure, and having, on a face extending between said two opposite faces, engagement means for securing it to the other wall structure constructed to provide clearance for movement in a direction at right angles to the sliding movement.

105 Signed at Jackson Heights, in the county of Queens and State of New York, this 15th day of December, A. D. 1925.

110 GEORGE W. DAVEY.
